UNITED STATES PATENT OFFICE.

HUGO GORDON DUVAL, OF NEW YORK, N. Y.

BINDER.

1,130,893.

Specification of Letters Patent.

Patented Mar. 9, 1915.

Application filed May 4, 1914. Serial No. 836,267.

To all whom it may concern:

Be it known that I, HUGO GORDON DUVAL, a subject of the King of Great Britain, residing at the city of New York, borough of Manhattan, in the county and State of New York, have invented certain new and useful Improvements in Binders, of which the following is a full, clear, and exact specification.

10 My invention relates to improvements in means for temporarily binding books within covers, and the same has for its object more particularly, to provide a simple, efficient and reliable device whereby a book may be 15 temporarily bound within a cover in such manner that the same may be readily detached therefrom when it is desired to change the book or remove the same for any reason.

Further said invention has for its object 20 to provide a binder comprising a cover, a support within the cover, and a removable attaching member adapted to engage said support and be passed through said cover, and then secured in place by a locking member which serves to lock said attaching member to said cover, and to secure the book duly 25 in position upon said support and embraced by attaching member and the cover.

To the attainment of the aforesaid objects 30 and ends my invention consists in the novel details of construction, and in the combination, connection and arrangement of parts hereinafter more fully described and then pointed out in the claims.

35 In the accompanying drawings, forming part of this specification, wherein like numerals of reference indicate like parts—Figure 1 is a sectional view taken on the line 1—1 of Fig. 2, showing one form of binder 40 constructed according to and embodying my invention; Fig. 2 is a top view thereof; Fig. 3 is a rear edge view of the binder, and Fig. 4 is an enlarged, horizontal section taken on the line 4—4 of Fig. 1 showing the upper 45 portion of the attaching member, and the manner of locking the same in position within the binder in order to secure a book therein.

In said drawings 10 designates a binder 50 comprising a front cover portion 11 and a back cover portion 12 foldably secured along their vertical edges to a back 13. The back 13 and the cover portions 11 and 12 are preferably formed of heavy binder's board or 55 analogous material and covered with cloth or other suitable material. Adjacent to the

lower portion of the back 13 is arranged an angular bracket 14 which has its vertical portion secured to the inner side of the back 13 by rivets 15, 15, or other suitable securing means. The horizontal portion of said bracket is tapered toward its free end and provided with a transverse slot 16. Adjacent to the upper edge of the back 13 is provided a vertically extending slot into which 60 is fitted an eyelet 17 having an elongated opening therein.

18 denotes an attaching member which is preferably made of a flat piece of metal provided adjacent to its lower end with oppositely arranged recesses 19, 19 which serve to produce a head 20 at the lower end of the attaching member 18 which head is united to said attaching member 18 by a reduced section 21. The other or upper end of said 70 attaching member 18 is provided with a projection 22 arranged at right angles to the body portion of said attaching member and provided at its extreme end with an aperture 23 to receive a suitable suspending or 80 supporting member 24 preferably made of cord in the form of a ring, or of leather or other suitable flexible material.

25 denotes a book which is secured within the binder 10 by having its lower edge supported upon the horizontal portion of the bracket 14, and its back embraced by the longitudinal portion of the attaching member 18 at or near the middle of said book. The upper edge of said book is confined below 85 the lateral projection 22 extending from the upper end of said attaching member 18.

In order to secure a book within the cover portion 10, it merely becomes necessary to remove the attaching member 24 from the 90 aperture 23 in said end 22, and thence draw said end 22 inwardly between the back and front cover portions of the binder until the same is wholly withdrawn from the eyelet 17 arranged in said back 13. Thereupon 100 said attaching member 18 is given a quarter of a turn whereby the head 20 at the lower end thereof will be brought into register with the transverse opening 16 provided in the free end of the bracket 14 and thus permit of the removal of said attaching member from said bracket 14. Thereupon the attaching member 18 is disposed between the pages of the book at a point near the middle of the book, and forced backwardly against 105 the back of the book as far as the same will go. The head 20 at the lower projecting end

of the attaching member 18 is thence reinserted into the transverse opening 16 in the bracket 14, and the attaching member together with the back 25 given a quarter of a turn which will bring the head 20 at right angles to the transverse slot 16 in said bracket 14 and prevent said attaching member being withdrawn from said bracket. The upper end 22 of the attaching member 18 is then passed through the eyelet 17 secured in the upper portion of the back 13, and the attaching member 24 passed through the opening 23 in said end 22 and the ends of said attaching member then secured together by means of a knot or other suitable fastening, as the case may be.

It will be observed that by means of my novel construction of attaching means the suspending and supporting member 24, by means of which the book and its binder may be supported or suspended, serves also to lock the attaching member in position within the binder and to hold the book firmly in place therein and below said attaching member.

When the parts have been adjusted as hereinabove described, it becomes impossible to remove the book from the binder without releasing or untying the supporting member 24 and removing the same entirely from the end 22 of said attaching member 18, as said supporting member 24 serves to lock the several parts securely in position.

Having thus described my invention, what I claim and desire to secure by Letters Patent is:

1. A binder comprising a back, a pair of covers thereon, a member rigidly secured to said back adjacent to one of its ends, an attaching member adapted to engage at one end with said member and at its other end to extend through said back adjacent to the other end of said back, and a suspending member engaging the end of said attaching member projecting beyond said back, substantially as specified.

2. A binder comprising a back, and a pair of covers connected thereto, a support rigidly secured to said back adjacent to its lower end, an attaching member adapted for detachable engagement with said support and having one end extending through said back, and a suspending member adapted to engage the portion of said attaching member extending through said back whereby to secure said attaching member to said binder and to secure a book in position below

said attaching member, substantially as specified.

3. A binder comprising a back and a pair of covers connected thereto; said back having an opening therein adjacent to its upper end, an angular support secured upon an inner side of said back adjacent to its lower end, an attaching member adapted to interlock at one end with said supporting member, and its other end to extend through the opening in the upper end of said back, and a securing member engaging the portion of said attaching member projecting beyond the rear of said back, substantially as specified.

4. A binder comprising a back and a pair of covers hinged thereto; said back having an aperture therein adjacent to its upper end, a bracket secured upon the inner side of said back adjacent to its lower end, a flat attaching member provided at one end with means adapted to interlock with said bracket, and at its upper end with an angular projection adapted to be passed through the opening in the upper portion of said back, and a detachable securing member adapted to engage the portion of said attaching member extending through said back, substantially as specified.

5. A binder comprising a back and a pair of covers hinged thereto, said back having a vertically extending slot therein adjacent to its upper end, an angular bracket rigidly secured upon the inner side of said back adjacent to the lower end thereof and provided in its free portion with a transversely extending slot, a flat, longitudinal attaching member provided at its lower end with a reduced portion adapted to interlock with the transverse slot in said bracket, a laterally projecting portion provided at the upper end of said attaching member adapted to be passed through the slot adjacent to the upper end of said back, and an attaching member removably secured to the free end of said laterally projecting portion extending beyond the rear of said back, substantially as specified.

Signed at the city of New York, in the county and State of New York, this 25th day of April, one thousand nine hundred and fourteen.

HUGO GORDON DUVAL.
